UNITED STATES PATENT OFFICE.

MAXMILIAN ERNST, OF CLEVELAND, OHIO.

DESIGN FOR A BOX-COVER.

SPECIFICATION forming part of Design No. 25,003, dated December 24, 1895.

Application filed May 9, 1895. Serial No. 548,774. Term of patent 7 years.

To all whom it may concern:

Be it known that I, MAXMILIAN ERNST, a citizen of the United States, residing at Cleveland, in the county of Cuyahoga and State of Ohio, have invented and produced a new and original Design for Box-Covers, of which the following is a specification, reference being had to the accompanying drawings, forming a part thereof.

10 Figure 1 is a picture of a box-cover made according to my design. Fig. 2 is a central vertical section of the cover applied to the box.

The box-cover *b* is circular or approximately circular in plan, and the upper or top 15 side thereof is convex and is suitably indented to form quite a number of rounded circular projections that have the general shape, re-

spectively, of a cherry, and the upper external surface of the cover is also provided with several narrow and comparatively short ridges 20 that extend from some of the cherry-representing projections and have the shape of and represent the stems of cherries.

What I claim is—

The design for a box-cover herein shown 25 and described.

In testimony whereof I sign this specification, in the presence of two witnesses, this 6th day of May, 1895.

MAXMILIAN ERNST.

Witnesses:

C. H. DORER,
L. WARD HOOVER.
